DESIGN FOR A DISPLAY BOX

Sylvanus F. Bowser, Fort Wayne, Ind.

Application March 30, 1934, Serial No. 51,250

Term of patent 14 years

To all whom it may concern:

Be it known that I, SYLVANUS F. BOWSER, a citizen of the United States, residing at Fort Wayne, in the county of Allen, and State of Indiana, have invented a new, original, and ornamental Design for a Display Box, of which the following is a specification, reference being had to the accompanying drawing, forming part thereof.

Figures 1 and 2 are perspective views taken from the front and rear, respectively, of a display box showing my new design, and

Figure 3 is a front view thereof.

The figure is mounted upon a cabinet which acts as a pedestal for the figure and into which the articles of the type displayed on the figure may be conveniently placed. The cabinet, which is shown in dotted lines, is not a material part of the design.

I claim:

The ornamental design for a display box as shown and described.

SYLVANUS F. BOWSER.
